FIG. I.

FIG. 2.

JOHN M. ELLIOTT Inventor

By Thomas R. Harvey

Attorney

Patented Aug. 16, 1927.

1,638,990

UNITED STATES PATENT OFFICE.

JOHN M. ELLIOTT, OF RIMINI, SOUTH CAROLINA.

WRENCH.

Application filed May 3, 1926. Serial No. 106,330.

The present invention relates to improvements in wrenches of the type embodying a slidable outer jaw, which is adjustable through the manipulation of a relatively rotatable handle or hand-piece operatively connected with the fixed jaw and co-acting with the slidable jaw through a screw bar.

By the utilization of the device of my invention a tool of this character is provided which requires but a minimum number of parts of simple construction and operation, and therefore may be manufactured at a low cost of production. The parts may readily be assembled for use and manipulated with facility in adjusting the jaws of the wrench, may with equal facility be detached when required, and means are provided whereby the operating parts are adequately lubricated and protected from accumulation of dust or dirt, as well as from rust.

The elements or features of the device are so associated and related as to provide a strong, durable, and reliable tool that may be manipulated by the use of both hands if necessary and may with facility be adjusted by the use of one hand only. The invention consists in certain novel combinations and arrangements of parts as will hereinafter be more fully set forth and claimed.

In the accompanying drawings I have illustrated one complete example of the physical embodiment of my invention wherein the parts are combined and arranged according to the best mode I have thus far devised for the practical application of the principles of my invention.

Figure 1 is a plan view of a wrench embodying my invention some of the parts being shown in dotted lines.

Figure 2 is a view partially broken away to disclose the operating parts of the wrench.

Figure 3 is a transverse sectional view at line 3—3 of Figure 2.

Figure 4 is a transverse sectional view at line 4—4 of Figure 1.

In the preferred form of my invention as illustrated in the drawings the outer sliding jaw 1 of usual type is fashioned integral with the stem 2, and the stem, at its end

opposite the jaw is fashioned with a longitudinally extending threaded socket 3. The stem may be rounded in shape, but in such event is provided with flat sides 4 in order that it may remain stationary while other parts of the wrench are being revolved, for

60 The complementary inner jaw 5 is the fixed jaw and is fashioned with an integral guide sleeve 6 in which the stem 2 reciprocates. The jaw 5 is provided with complementary, inner flat faces for engagement with the faces 4 of the stem to permit relative slide movement of the stem in the sleeve and to prevent turning of the sleeve on the stem.

65 At one side of its inner end the guide sleeve 6 is fashioned with exterior, arcuate flange 7, and the flange is fashioned with an interior arcuate flange 8 which provides an inner arcuate groove 9 on the flange 7, for co-action with the hand piece or handle 10.

70 A portion of the handle is of tubular form to enclose the socket-end of the stem 2, and the handle, which is rotatable on the stem and with relation to the sleeve, also guides 75 the stem in its sliding movement.

75 Within the tubular end of the handle is carried a screw bar 11 having a head 12 to fit neatly therein, and a pin 13 is driven through transverse openings in the tubular handle and through an aperture in the head for securing the screw bar and its head in rigid relation to the tubular handle. The screw bar is threaded into the threaded socket 3 of the stem 2, and it will be apparent that the tubular handle in co-action with the rounded stem is adapted to guide the handle and maintain it in position against wobbling or lost motion on the stem as a guide for the screw bar as it is turned in its socket.

80 For coupling the handle with the guide sleeve I employ an annular, exterior groove 14 at the end of the tubular handle, in which the arcuate lug 8 neatly fits, and the annular bead 15 formed by the groove at the end of the tubular handle, turns in the complementary groove 9 of the flanged sleeve. The end of the tubular handle abuts 85 against the end face of the sleeve for frictional engagement when the handle is turned, and the arcuate lug 8 on the groove 14, not only guides the rotating handle, but retains the handle in its relation to the sleeve.

100 Thus for moving the slide jaw 1 relatively to the fixed jaw 5 the tubular handle is grasped in the hand and turned to the right or to the left as desired to close or to open the jaws.

105 The parts may be lubricated by applying oil or grease to the screw bar and to the ex-

terior surface of the stem, and as these parts are enclosed within other parts of the tool they are protected from accumulation of dust or grit, and also against rust.

If necessary, the handle and guide jaw with its sleeve may be detached from the stem by turning the screw bar out of its socket in the stem whereupon the tubular handle hand sleeve are uncoupled, and of course, with the parts in operative position, the handle may be turned to close the sliding jaw against the fixed jaw.

The various parts of the tool are finished in such manner as to insure a close fit throughout, and a stable, durable, and readily manipulated wrench is thus provided.

Having thus fully described my invention, what I claim as new and desire to secure by Letters Patent is—

1. The combination with a sliding jaw, an integral stem having a threaded socket,

and a non-rotatable guide sleeve on the stem having a fixed jaw, of a tubular handle rotatable on the stem, a screw bar within the handle having a head fixed thereto and operable in the threaded socket, and coupling means between the tubular handle and sleeve.

2. The combination with a sliding jaw having an integral stem and a threaded socket in the stem, of a fixed jaw having a guide sleeve on the stem and a lug on said sleeve, a tubular handle having an annular groove for said lug and rotatable on the stem, a screw bar within the handle operable in the threaded socket, a head on the bar, and means for rigidly fastening said head within the handle.

In testimony whereof I have affixed my signature.

JOHN M. ELLIOTT.
